UNITED STATES PATENT OFFICE.

VICTOR C. RUMBERG, OF OGEMA, WISCONSIN.

COMBINATION DOOR LOCK.

Application filed May 13, 1922. Serial No. 560,640.

To all whom it may concern:

Be it known that I, VICTOR C. RUMBERG, a citizen of the United States, residing at Ogema, in the county of Price and State 5 of Wisconsin, have invented a new and useful Combination Door Lock, of which the following is a specification.

The device forming the subject matter of this application is a lock, and the invention aims to provide novel means whereby the bolt of the lock may be controlled through the instrumentality of a permutation mechanism. Another object of the invention is to provide novel means whereby 15 the bolt of the lock may be manipulated from the inside of the door even though the bolt may be held against movement from the outside of the door.

It is within the province of the disclosure 20 to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that, within the scope of what is claimed, 30 changes in the precise embodiment of the invention shown can be made without departing from the spirit of the invention.

In the accompanying drawings.

Figure 1 shows in elevation, one side of 35 a door carrying a lock constructed in accordance with the invention; Figure 2 is an elevation showing the opposite side of the door and the lock from that depicted in Figure 1; Figure 3 is an elevation showing 40 a portion of the casing of the lock, and parts therein, sundry elements appearing in section; Figure 4 is a section on the line 4—4 of Figure 2; Figure 5 is a section on the line 5—5 of Figure 1; Figure 6 is a section 45 on the line 6—6 of Figure 1. Figure 7 is an elevation showing the arm which operates the bolt, the neck of the knob appearing in section. Figure 8 is a sectional view illustrating a latch which may be mounted 50 in the slide, if desired. Figure 9 is a cross section taken through the slide of Figure 8.

The numeral 1 marks a door, and the numeral 2 designates a jamb wherewith the door cooperates, the jamb 2 carrying a 55 keeper 3 of any desired construction. The

lock forming the subject matter of this application comprises a casing including a face plate 4 secured at 5 to the outer side of the door 1, the face plate carrying a frame 6 which may be mortised into the door 1. The 60 frame 6 is closed by a back plate 7 held in place by securing elements 8 adapted to engage lugs 9 on the frame 6, and to engage a post 10 projecting from the face plate 4. The plate 11 is secured at 12 to the inner 65 side of the door 1.

The numeral 14 marks an outer knob journaled in the face plate 4 and comprising a neck 17. A spindle 15 of rectangular cross section is inserted into the neck 17 and is 70 held therein by a securing element 21. An arm 16 is provided, the same having a hub 18 into which the neck 17 of the knob 14 extends. In the outer surface of the hub 18 of the arm 16 there is a transverse seat 19, 75 as shown in Figure 7 of the drawings. A cross pin 20 is mounted in the hub 18 of the arm 16 and is received in the seat 19. The hub 18 of the arm 16 carries a transverse sleeve 22 journaled in a bushing 23 seated 80 in the door 1, and journaled in the side plate 11. The bushing 23 may be omitted if desired. A securing element 24 is mounted in the inner end of the spindle 15 and retains a washer 25. A compression spring 85 26 surrounds the spindle 15, one end of the spring abutting against the washer 25, and the other end of the spring abutting against the hub 18 of the arm 16. The numeral 27 marks an inner knob, carrying a sleeve 28 90 wherein the sleeve 22 of the arm 16 is received, a securing element 29 connecting the sleeves 28 and 22, and there being a plurality of openings 100, in the sleeve 22, for the reception of the securing element 29 to 95 permit the use of the device on doors of different thicknesses. The frame 6 has a stop 30 against which the arm 16 abuts when the arm is swung to the left (Figure 3). In the free end of the arm 16 there is a notch 100 31. An opening 32 is fashioned in the arm 16 and receives pivotally, a cross piece 33 on the inner end of a bolt 34 adapted to co-operate with the keeper 3, the head of the bolt 34 being slidable in a guide 35 on the 105 face plate 4. The head of the bolt 34 is provided with stops 44 which, coacting with the frame 6 limit the forward movement of the bolt. A finger 36 projects from the hub 18 of the arm 16 and is engaged by a 110

spring tongue 37 mounted to slide on a rib 38 projecting from the plate 4, one end of the tongue being secured at 39 to the plate 4, the plate having a projection 40 which, 5 overhanging the tongue 37 holds the tongue for flexure, under the action of the finger 36. A detent 41 is mounted pivotally at 10 42 on the plate 4 and has a shoulder 43 adapted to cooperate with the notch 31 in the arm 16. The detent 41 has a finger 45 which projects beyond the shoulder 43. The 15 back plate 7 carries a bearing 46 wherein a tubular shaft 47 is journaled, the shaft having an arm 48, operating behind the 20 detent 41 and adapted to cooperate with the finger 45 in a way which will be set forth hereinafter. A compression spring 49 cooperates with the frame 6 and with the detent 41 to swing the detent upwardly 25 until the detent abuts against the tubular shaft 47, as shown in Figure 3. A spindle 50 is journaled and held for rotation in the plate 11 and carries an outer turning head 51, the spindle being held removably, but 30 against rotation, in a rectangular opening 52 in the shaft 47. A stop 53 projects from the plate 4 and is adapted to be engaged by the arm 48 on the shaft 47, when the arm is swung downwardly from the position shown in Figure 3.

The plates 4 and 7 have matching flanges 54 wherein a slide rod 55 is mounted for right line reciprocation. The slide 55 has a depending extension 56 adapted to engage 35 the end of the detent 41. The rod 55 has an enlarged head 101, from which the member 56 projects, the head having a rib 63 (Figure 5) mounted to slide in an internal guideway 64 formed in the plate 4. On its 40 outer surface, the plate 4 is supplied with a rib 59. There is a slot 58 in the rib 59. A stud 57 projects from the head 101 and is movable in the slot 58. At its outer end, the stud 57 is supplied with a knob 60. 45 A foot piece 61 is disposed between the knob 60 and the rib 59 and is slidable in a superficial slot 62 formed in the rib, the foot piece being carried by the stud 57. The slide rod 55 is supplied with projections 65. 50

Permutation tumblers 66 are located between the flanges 54 and are journaled on the slide rod 55. The tumblers 66 are maintained in axial alinement, not only by the 55 slide rod 55, but, as well, by interengaging annular ribs and grooves 67 on the abutting faces of the tumblers. The tumblers 66 have recesses 68 wherein the projections 65 on the slide rod 55 are received when the tumblers 60 are rotated. The tumblers 66 have transverse slots 69. When the slots 69 are alined, the projections 65 on the slide rod 55 may move through the slots, it being possible, thus, for the rod 55 to have longitudinal 65 movement. The face plate 4 has an open-

ing 70 through which the tumblers 66 are exposed. There is a flange 71 on the plate 4 at one end of the opening 70, the flange carrying an index 72 adapted to cooperate with characters 73 on the tumblers 66. A retaining bar 74 is secured at 75 to the inner surface of the plate 4 and holds the spring 76 adapted to bear on the periphery of the tumblers 66.

Let it be supposed that selected ones of the characters 73 on the tumblers 66 have been lined up with the index 72 so that the slots 69 in the tumblers are alined, the slide rod 55 having been moved to the right (Figure 3), until the projections 65 are 80 located in the recesses 68, motion being imparted to the slide rod through the instrumentality of the knob 60 on the stud 57. The projection 56 on the slide rod 55 has been moved so far to the right that the 85 spring 49 has raised the detent 41 until the shoulder 43 on the detent is out of the path of the upper end of the arm 16. When the knob 14 is rotated, the cross pin 20 in the neck 17 of the knob being received in the 90 seat 19 of the hub 18 of the arm 16 imparts swinging movement to the arm 16, the arm 16 retracting the locking bolt 64, the spring 37 serving to return the locking bolt to the 95 position shown in Figure 3, when the knob 14 is released. When the knob 27 is turned, the sleeve 22 is rotated, and swinging movement is imparted to the arm 16, since the sleeve 22 is integral with the hub 18 of the arm. The bolt 34 in view of the foregoing 100 may be retracted from either side of the door.

Suppose, however, that it is desired to lock the bolt 34 in advanced position. Then, the slide rod 55 is moved to the left (Figure 3) and the tumblers 65 are rotated, the tumblers cooperating with the projections 65 on the slide rod 55 to hold the slide rod in the position to which it may have been advanced, toward the left (Figure 3). 105 When the slide rod 55 is moved to the left, the projection 56 on the slide rod engages the detent 41 and swings the detent 41 downwardly, the shoulder 43 on the detent engaging the arm 16, within the notch 31, 110 and the spring 49 being compressed. The arm 16 cannot now swing counter-clockwise (Figure 3) and the bolt 34 is held in advanced position, in engagement with the keeper 3 on the jamb 2. When it is 115 desired to set the locking bolt 34 free, the proper combination is set up by alining certain of the characters 73 on the tumblers 66 with the index 72, the slots 69 in the tumblers then being alined, to receive the 120 projections 65 on the slide rod 55, whereupon the slide rod may be moved to the right, into the position shown in Figure 3, the spring 49 swinging the detent 41 upwardly, and setting the arm 16 free, so that 125 130

when either of the knobs 14 or 27 is rotated, the bolt 34 may be retracted through the instrumentality of the arm 16.

It may be desirable, at times to dead-lock the bolt 34 from the inside of the door. Under such circumstances, rotation is imparted to the spindle 50 and to the shaft 47, by way of the head 51, the arm 48 on the shaft 47 moving downwardly into abutment with the stop 53. When the arm 48 swings downwardly, the arm engages the finger 45 on the detent 41 and swings the detent downwardly, until the shoulder 43 on the detent is engaged with the upper end of the arm 16, the arm 16 thus being held against swinging movement and it being impossible to retract the bolt 34 by either of the knobs 14 or 27.

Let it be supposed that the detent 41 has been swung downwardly, to engage with the arm 16, the detent being held in engagement with the arm 16, through the instrumentality of the projection 56 on the slide bolt 55. Suppose, further that it is desired to retract the bolt 34 from the inside of the door. It is obvious, that if the door is locked a person on the inside of the door cannot get at the permutation tumblers 66, and release the slide rod 55 because the tumblers are accessible from the outer side of the door only. In order to actuate and retract the bolt 34, under the conditions above specified, the knob 27 is pulled outwardly, the arm 16 moving to the right (Figure 6) along with the knob 27, because the sleeve 28 of the knob is connected at 29 to the sleeve 22 on the hub 18 of the arm 16. When the arm 16 is carried to the right (Figure 6) a short distance, the seat 19 in the hub 18 of the arm 16 is disengaged from the cross pin 20 in the neck 17 of the knob 14, and, at the same time, the arm 16 is moved to the right (Figure 6) until it is clear of the detent 41, the arm 16 sliding on the cross head 33 of the arm 16. When the arm 16 has been moved to the right (Figure 6) until it is clear of the detent 41, the knob 27 may be rotated to swing the arm 16 counter clockwise (Figure 6), thereby to effect a retracting of the locking bolt 34.

The cross pin 20, carried by the knob 14, cooperating with the seat 19 in the hub 18 of the arm 16, forms a connection between the knobs 27 and 14, by way of the sleeves 18 and 22 so that the arm 16 may be swung counter-clockwise, and the bolt 34 retracted, from either side of the door, when the detent 41 is in the raised position shown in Figure 3 and is out of engagement with the arm 16.

In Figure 8, the plate, corresponding to the plate 4, is marked by the numeral 90, the flanges appearing at 91 and corresponding to the parts 54. The tumblers are marked by 65 the numeral 92. The slide, corresponding to

the part 55 is shown at 93. A latch 94 is mounted for reciprocation in the slide 93, transversely thereof, and has projections 95 corresponding to the parts 65 and adapted to cooperate with the tumblers. The latch 94 is advanced by a spring 96 located within the slide 93, the spring being held in place by a closure 97 in the slide 93 or in any other suitable way. Suppose that the tumblers have been rotated so that the notches in the tumblers are not in alinement, as shown in Figure 8. Suppose, further that it is desired to move the slide to the left, from the position shown in Figure 3 to effect a locking operation. The projections 95 on the latch 94 are beveled, and the latch 94 may be pushed to the left (Figure 8), thereby enabling the projections 95 to engage with the tumblers, and to prevent the slide 93 from moving to the right. The operator, in view of the foregoing, has at his command, a means whereby the device may be locked without setting up on the tumblers, such a combination as will align the notches in the tumblers. 90

What is claimed is:—

1. In a device of the class described, a casing; an arm mounted to swing on the casing; means for swinging the arm; a locking bolt controlled by the arm; a detent pivoted on the casing and movable into engagement with the arm; a slide mounted to reciprocate on the casing and cooperating with the detent to cause the detent to engage the arm; and permutation mechanism controlling the slide. 100

2. In a device of the class described, a casing; an arm mounted to swing on the casing; means for swinging the arm; a locking bolt controlled by the arm; a detent pivoted on the casing and movable into engagement with the arm; a slide mounted to reciprocate on the casing and cooperating with the detent to cause the detent to engage the arm; means for holding the slide against reciprocation; and a dead lock on the casing and engaging the detent to move the detent into engagement with the arm, and to hold the detent engaged therewith, when the slide is in such a position that the detent is not swung, by the slide, into engagement with the arm. 115

3. In a device of the class described, a casing; a swinging arm; a bolt controlled by the arm; a detent movable on the casing and adapted to engage the arm; rotatable members journaled in the casing, one of said rotatable members carrying the arm; interengaging elements on said rotatable members and connecting them for rotation, 120 whereby motion may be transmitted to the arm from either rotatable member when the detent is disengaged from the arm, the arm-carrying rotatable member being longitudinally movable, to disengage said interen- 125

gaging elements, and to move the arm clear of the detent when the detent is engaged with the arm.

4. In a device of the class described, constructed as set forth in claim 3, and further characterized by the provision of a slide mounted to reciprocate on the casing and cooperating with the detent to cause the detent to engage the arm; and permutation mechanism controlling the slide.

5. A device of the class described constructed as set forth in claim 3, and further characterized by the provision of a slide mounted to reciprocate on the casing and cooperating with the detent to cause the

detent to engage the arm; permutation mechanism controlling the slide; and a dead latch on the casing and engaging the detent to move the detent into engagement with the arm and to hold the detent engaged therewith, when the slide is in such a position that the detent is not swung, by the slide into engagement with the arm.

In testimony that I claim the foregoing as my own, I have hereto affixed my signature in the presence of two witnesses.

VICTOR C. RUMBERG.

Witnesses:

ALEX W. NELSON,
WALTER NELSON.
